Specification for Design.

Patented Oct. 12, 1909.

Application filed June 11, 1909. Serial No. 501,664. Term of patent 7 years.

To all whom it may concern:

Be it known that I, ALFRED A. BOECK, a subject of the Emperor of Germany, residing in the city of New York, borough of Manhattan, in the county and State of New York, have invented a new, original, and ornamental Design for a Fabric for Window-Shades and the Like, of which the following is a specification, reference being had to the accompanying drawing, forming a part thereof.

The figure is a fragmentary view of a fabric for window shades and the like, illustrating my new design.

I claim:

The ornamental design for a fabric for window shades and the like, as shown.

ALFRED A. BOECK.
